UNITED STATES PATENT OFFICE

147,478

DESIGN FOR A NECKTIE

Alfred Frank Taborski, Buffalo, N. Y.

Application June 29, 1944, Serial No. 114,247

Term of patent 3½ years

(Cl. D3—16)

To all whom it may concern:

Be it known that I, Alfred F. Taborski, a citizen of the United States, residing at Buffalo, in the county of Erie and State of New York, have invented a new, original, and ornamental Design for a Necktie, of which the following is a specification, reference being had to the accompanying drawing, forming a part thereof.

The essential features of my design reside in the portions shown in solid lines.

I claim:

The ornamental design for a necktie, as shown and described.

ALFRED FRANK TABORSKI.
